CLAIM

The ornamental design for an in-line fuse holder, substantially as shown and described.

DESCRIPTION

FIG. 1 is a perspective view of an in-line fuse holder embodying the present design, showing the holder in its closed position;

FIG. 2 is a front elevational view thereof;

FIG. 3 is a right side elevational view thereof;

FIG. 4 is a top plan view thereof;

FIG. 5 is a bottom plan view thereof;

FIG. 6 is a rear elevational view thereof;

FIG. 7 is a left side elevational view thereof; and

FIG. 8 is an enlarged fragmentary perspective view thereof, shown in an open position.
